Ohio, a corporation of Maryland

Original application January 10, 1930, Serial No.
419,938. Divided and this application October
28, 1933, Serial No. 695,651

2 Claims. (Cl. 235—27)

This invention relates to registers and like machines and more particularly refers to improvements in machines of the type disclosed in Letters Patent of the United States No. 1,816,263 issued to William H. Robertson on August 4, 1931, and in application for Letters Patent of the United States Serial Nos. 169,583, 172,660 and 303,250 filed February 19, 1927, March 4, 1927, and August 31, 1928, respectively by William H. Robertson; and is a division of the application for United States Letters Patent of William H. Robertson Serial No. 419,938 filed January 10, 1930.

The main object of this invention is to provide a novel interlocking feature between the keys in what is known in the art as a divided or split bank of keys.

More specifically it is an object of this invention to provide novel means in a divided or split bank of keys to compel the depression of a certain one of the keys before any of the remaining keys in that bank can be depressed.

Another object of this invention is to provide a plurality of shiftable detent bars associated with a divided or split bank of keys which detent bars coact with one another in such a manner as to cause a key associated with one bar to be released upon depression of a key which coacts with the other bar.

With these and incidental objects in view, the invention includes certain novel features of construction and combinations of parts the essential elements of which are set forth in appended claims and a preferred form of embodiment of which is hereinafter described with reference to the drawing which accompanies and forms part of this specification.

In said drawing:

Fig. 1 is a detail view in right elevation of the divided or one-half cent key bank.

Fig. 2 is view partly in section and partly in front elevation taken generally on line 2—2 of Fig. 1.

Fig. 3 is a fragmentary view of the split detent bar associated with the keys in the divided or one-half cent key bank.

Detailed description

The machine to which the present invention is adapted to be applied is used to issue postage permits for the United States mail. It frequently happens that the amount of postage required ends in a fraction of a cent usually one-half cent. Therefore, a half-cent key is provided in the machine of the present invention to effect the registration of such fractional amount. The one-

half cent key 41 (Fig. 1) is located in the "5" position in the bank of keys shown in Fig. 1.

This bank of keys is what is known in the art as a divided or split bank. This key 41 is slidably mounted in a key frame 81 supported on cross rods 61 and 62. A spring (not shown) coiled about the shank of this key restores it to its normal undepressed condition and retains it in such position.

When the half-cent key is depressed, a key pin 10 82 (Figs. 1 and 3) in the shank thereof engages the beveled edge of a shouldered projection 83 on a flexible detent bar 84 and cams this bar downwardly until the pin 82 has passed the shoulder on the projection 83 whereupon a spring 85 15 draws the detent bar upwardly and engages the shoulder on the projection 83 over the key pin 82 to retain the key 41 in its depressed position. The detent bar 84 is slotted for slidable mounting on supporting studs 86 and 87 projecting from the 20 frame 81.

Additional keys 42 and 43 known as the "in- 25 sured" key and the "C. O. D." key respectively are also similarly mounted to slide in the key frame 81. The key pin 88 on the shank of the "in- 25 sured" key 42 and the key pin 89 on the shank of the "C. O. D." key 43 cooperate with shouldered projections 95 on a slotted detent bar 96 shorter than and arranged beside the bar 84 and slidably mounted on the stud 86 and on a supporting stud 30 97 also projecting from the key frame 81.

When one of the keys 42 or 43 is depressed the pin 88 or 89 depending upon which key is depressed cams the short auxiliary detent bar 96 downwardly until the key pin on the particular 35 key depressed has passed the shoulder on the projection 95 cooperating therewith, whereupon a spring 98 draws the auxiliary detent bar 96 upwardly to engage the shoulder over the key pin on the shank of the depressed key to hold the 40 key in its depressed position. The upper end of the auxiliary detent bar 96 under the influence of the spring 98 normally abuts a stop stud 99 projecting laterally from the main detent bar 84. When one of the keys 42 or 43 is depressed its 45 key pin 88 or 89 operating against the shouldered projection 95 moves the auxiliary detent bar 96 downwardly thereby shifting its upper end from contact with the stud 99. If after a key 42 or 43 is depressed the one-half cent key 41 is de- 50 pressed, the stud 82 thereon acting on the beveled edge of its shouldered projection 83 moves the main detent bar 84 downwardly far enough to cause the stop stud 99 to impinge against the end of the auxiliary detent bar 96 and shift this aux- 55

iliary bar still farther downwardly a distance sufficient to remove the shouldered projection 95 from engagement with the pin 88 or 89 of the depressed key 42 or 43 thereby releasing such key 5 to the action of its restoring spring.

This feature makes it necessary to depress the one-half cent key 41 before depressing either the "insured" key 42 or the "C. O. D." key 43 when registering transactions involving an insured or 10 C. O. D. parcel when the amount of the postage ends in a fraction of a cent.

A locking bar 100 is provided for the keys in the divided bank to lock the one-half cent key 41, the "insured" key 42, and the "C. O. D." key 15 43 against depression or release during operations in the machine. The locking bar 100 is moved upwardly at the instant the machine is released by a bail 123 which contacts a swinging arm 296 forked to embrace a stud 297 on the locking bar 20 100 and shift the locking bar upwardly to engage hooked projections 101 on the locking bar 100 beneath the pin or pins of the undepressed key or keys and over the pin or pins of the depressed key or keys to lock all of the keys in the positions 25 occupied when the machine is released for operation.

Near the end of the operation both the flexible 30 detent bar 84 is moved downwardly by the restoring arm 327 engaging a stud 328 in said bar in the manner fully described in the parent case, and the locking detent bar 100 is moved downwardly by the spring 70, to release the depressed 35 keys which immediately restore to their normal positions under the influence of their individual springs, and to free the undepressed keys so that they may be depressed preparatory to the next

operation. When the main detent bar 84 is moved downwardly the stud 99 thereon contacts the end of the short auxiliary detent bar 96 and carries this detent bar therewith to release the keys 42 or 43 if depressed. The springs 85 and 98 then restore their respective detent bars 84 and 96 to their normal positions. 5

While the form of mechanism herein shown and described is admirably adapted to fulfill the objects primarily stated, it is to be understood 10 that it is not intended to confine the invention to the one form of embodiment herein described for it is susceptible of embodiment in various forms all coming within the scope of the claims 15 which follow.

What is claimed is:

1. In a machine of the class described; the combination with a plurality of groups of keys; and a plurality of detent bars, one for each group of keys to retain the keys in depressed position; of 20 a projection on one of the detent bars adapted, when said bar is moved to release the depressed key in its group of keys, to move the other detent bar; and means separate from the keys to actuate the detent bar carrying the projection. 25

2. In a machine of the class described, the combination of a single row of keys; a plurality of shiftable detent bars associated therewith, certain keys coacting with one of said detent bars, and the remaining key coacting with another of such detent bars; and means on one of such bars extending across the other of said bars to shift the latter and release the key associated therewith when a key coacting with the first named detent bar is depressed. 30 35
